RAYMOND R. MACHLETT, OF NEW YORK, N. Y., ASSIGNOR TO RAINBOW LIGHT, INC., OF LONG ISLAND CITY, NEW YORK, A CORPORATION OF NEW YORK

PROCESS OF MANUFACTURING LUMINOUS TUBES AND APPARATUS FOR CARRYING THEM OUT

Application filed August 17, 1928. Serial No. 300,234.

My present invention relates to the process of manufacturing luminous electrical discharge tubes which contain a rarefied atmosphere comprising an inert gas such as neon or argon or a combination of such gases to which a small quantity of mercury vapor is added for the purpose, among others, of increasing the range of colors.

In the manufacture of such tubes it is essential to remove every possible trace of gas or moisture, not only from the interior but from the walls and electrodes, before the rare gas or the mercury is injected. For commercial reasons it is also very desirable to perform the operations of exhausting, purifying and filling the tube in the simplest, quickest and most convenient way, without the necessity for further aging or seasoning and to perform these operations upon several tubes at the same time, thereby securing a more uniform product and achieving a substantial saving of time in manufacture over the customary practice of processing each tube separately.

To accomplish these results I have devised a process and the apparatus for performing it which permits of the simultaneous heating, exhausting and filling of a number of luminous tubes which is particularly effective in the processing of tubes in which mercury and mercury vapor are to be injected, as well as a rare gas or combination of rare gases. This process and the apparatus for performing it is the subject of this invention.

In order that my invention may be clearly understood, attention is directed to the accompanying drawing in which

Fig. 1 is a perspective view of a suitable oven for processing the tubes, in which three tubes are shown, the front of the oven being lifted to disclose the interior.

Fig. 2 is a side elevation on a larger scale showing a single tube in process of manufacture, and

Fig. 3 is a perspective view illustrating the manner in which a single mercury reservoir may be used in simultaneously processing several tubes, as in Fig. 1.

In all of these views corresponding parts are represented by the same numerals.

While the shape of the tubes is immaterial, the drawing illustrates tubes 1 having a straight central portion and enlarged ends 2. In each of the enlarged ends is the usual electrode.

In processing the improved tubes a number of them are mounted side by side as shown in Fig. 1 and provided with tubulations 3 leading to a common tube or manifold 4 and supported by hangers 5 within a suitable oven 6. For the purpose of illustration I show three of these tubes in the oven 6, although the number may be more or less. By thus simultaneously processing a plurality of tubes I very greatly extend the capacity of the oven and reduce the time required to perform the necessary operations.

Tube 4 leads to the exhaust pump which may be of the usual type for producing the necessary high vacuum. Tube 4, at some point outside of the oven is joined by a branch tube 7 leading to the supply of neon or other gas, with which the tube is ultimately to be filled.

The tubulation 3 which is preferably positioned at about the center of the straight portion of each tube 1 is provided with a depending portion 8 which serves as a reservoir for mercury. The depending portion 8 of each tubulation is surrounded by a heat insulating jacket 9 which may be conveniently made of asbestos paper rolled to form a heavy walled sleeve.

The oven 6 is heated in any suitable way, such as by means of gas jets 10 positioned below a perforated partition 11. It is also equipped with a door 12 which is provided with one or more mica covered openings 13 so that the tubes within the oven may be observed.

The electrodes of the tubes are connected to a suitable source of electric current by conductors 14 leading to the secondary 15 of a transformer, the primary 16 of which is in circuit with a suitable source of alternating current 17. Each of the tubes has similar electrical connections and the conductors may, obviously, be connected in multiple with a single secondary.

Assuming that the tubes are supported

within the oven as shown in Fig. 1, the process is carried out as follows:

The asbestos insulating sleeves 9 are saturated with water and placed around the lower part of the tubulations 8. The oven is closed and heating begun. The pumping apparatus is then started and air will be exhausted simultaneously from all of the tubes. When the pressure has been sufficiently reduced all of the electrodes of all of the tubes are brought to a red heat by the passage of a heavy current therethrough in order to drive off gases occluded within the electrodes. The current employed for this purpose is substantially greater than the normal current with which the tube is designed to operate. Thus the normal current in operation will not tend to drive off residual impurities.

During the next stage of the process the temperature of the oven is slowly raised to a degree sufficiently high to drive off gases occluded within the walls of the tubes, which temperature is higher than that at which the mercury within the depending portion 8 of the tubulation 3 would vaporize were it not for the water saturated asbestos insulating sleeve 9 which surrounds each tubulation. The oven temperature during this stage may for example be from 450 to 475° centigrade. I have found that at these temperatures a small amount of alkali metal, which is always held in a free state in the glass walls of the tubes, is vaporized and permeates the interior of the tubes, acting as a purging agent for the interior of the tube.

After this is accomplished the heat is turned off, the oven door opened and the insulating sleeves removed. The oven is then closed again and the temperature raised sufficiently to vaporize the mercury, the vapor of which will pass into and throughout the tube. Only the temperature necessary to produce vaporization will be required. The heat is then again turned off. After a short time the oven door is again opened and the oven temperature is allowed to drop to below 250° after which the electrodes are again heated to a red heat and the pumping continued until the highest possible vacuum has been obtained. Then the tube is flushed out with a quantity of pure gas, the pump shut off and pure gas admitted to the desired pressure. The tube is then sealed off at 18. A small amount of the mercury in portion 8 of tubulation 3 is then poured into each tube and it is then sealed off from the tubulation 3. The tube is now ready for use without further aging or seasoning.

Although I have referred to the tubes as having interior electrodes it will be seen that if they are provided with exterior electrodes instead they may be processed in the same way and with the same advantages as to facility of operation and saving of time.

65 A modification of the above arrangement

is shown in Fig. 3 wherein a single tubulation or reservoir for mercury has been substituted for the individual tubulations associated with each tube as shown in Fig. 1. The single tubulation communicates with all of the tubes through manifold 4 and only one insulating jacket is required. Otherwise, the process remains unaltered.

It will be seen that a number of tubes can be processed at once and the mercury vapor injected therein coincidentally with the cleansing process, thus doing away with special treatments which have been considered necessary.

Having now described my invention what I claim is:—

1. The method of processing a luminous tube of the class described, said tube being provided with an auxiliary tubulation containing mercury which consists in placing said tube and tubulation within a heating oven, in insulating the tubulation from the effects of heat, in heating the tube to a temperature higher than that at which mercury vaporizes, in removing said protecting means from said tubulation and subjecting it to heat so that the mercury is vaporized and diffused throughout the tube.

2. The method of processing a luminous tube of the class described provided with an auxiliary tubulation containing mercury which consists in placing said tube and tubulation within a heating oven, in creating a partial vacuum within the tube, in heating the electrodes by passing a strong electric current between them to remove occluded gases therefrom, in heating the tube to remove occluded gases therefrom, said tubulation being insulated from the source of heat, in removing said insulation from said tubulation, in heating the tubulation to vaporize the mercury therein and to cause the vapor to pass into and diffuse through the tube.

3. The method of simultaneously processing a multiplicity of luminous tubes of the class described each tube being provided with an auxiliary tubulation containing mercury, which consists in placing said tubes and tubulations within a heating oven, in insulating said tubulations from the effect of heat, in simultaneously heating all of said tubes to a temperature higher than that at which mercury vaporizes, in removing the insulation from said tubulations and in heating said tubulations to a temperature at which the mercury therein will vaporize.

4. The method of simultaneously processing a multiplicity of luminous tubes of the class described, which consists in connecting each of said tubes respectively to auxiliary tubulation containing mercury, in connecting said tubes to a common manifold, in placing said tubes, tubulations and manifold in a heating oven, in connecting said manifold to a vacuum pump, in insulating said tubulations

from the effects of heat, in creating a partial vacuum therein while heating said tubes, in passing a heavy electrical current between the electrodes of the tubes to heat them to incandescence for the purpose of freeing them 5 from impurities, in raising the temperature of the tubes to a degree above that at which mercury vaporizes, in removing the insulation from the tubulations, in heating the tubes and tubulations until the mercury vaporizes 10 and the vapor diffuses through the tubes, in reducing the temperature of the oven, in again heating the electrodes to red heat by the passage of current between them, in exhausting the tubes to a high vacuum, in flushing 15 the tubes with a quantity of the rare gas with which they are to be filled, in filling the tubes with the rare gas to the desired pressure, in sealing off the tubes from the common manifold, in pouring into the tubes a small 20 quantity of unvaporized mercury from its tubulation and in sealing off the tubes from the tubulations.

5. The method of processing a multiplicity 25 of luminous tubes of the class described which consists in connecting said tubes in multiple to a manifold, in connecting to each of said tubes a reservoir containing mercury, in insulating said reservoirs from the effects of 30 heat, in placing said tubes, manifold and reservoirs within a heating oven and connecting said manifold to a vacuum pump, in creating a partial vacuum within said tubes, in heating said electrodes to a red heat to free 35 them from impurities by passing a heavy electric current through them, in heating the tubes to a temperature of approximately 450° centigrade for approximately ten minutes, in removing the insulation from the 40 mercury reservoirs, in raising the temperature of the tubes and the reservoirs to a temperature at which the mercury within the reservoirs will be partially vaporized and diffused through the tubes, in reducing the 45 temperature of the tubes to approximately 250° centigrade and again heating the electrodes to red heat by the passage of current at this oven temperature, in creating a high vacuum within said tubes, in flushing out the tubes with 50 a quantity of the pure gas with which they are to be filled, in filling the tubes with pure gas to the desired pressure, in sealing off the tubes from the manifold, in pouring into each tube a small quantity of the unvaporized 55 mercury from its reservoir and in sealing off said tubes from said reservoirs.

6. Means for simultaneously processing a multiplicity of luminous tubes of the class described comprising a heating oven in which 60 the tubes are suspended, a common manifold connecting the tubes in multiple with a vacuum pump, an auxiliary tubulation containing mercury communicating with each tube, means for insulating said tubulations from 65 the effect of heat when the temperature of the

oven is raised above that at which mercury vaporizes and means for admitting into the tubes a rare gas of the atmosphere.

7. Means for vaporizing mercury contained within an auxiliary tubulation communicating with a luminous tube of the class described, comprising an oven in which the luminous tube and tubulation are placed, a sleeve of heat insulating material surrounding the tubulation and adapted to insulate it from the heat when the oven is raised to a temperature higher than that at which mercury vaporizes said sleeve being subsequently removed to expose the tubulation to the heat of the oven.

8. Means for vaporizing mercury contained within an auxiliary tubulation communicating with a luminous tube of the class described, comprising an oven in which the luminous tube and tubulation are placed, a removable sleeve of heat insulating material surrounding the tubulation and adapted to insulate it from the heat when the oven is raised to a temperature higher than that at which mercury vaporizes said sleeve being subsequently removed to expose the tubulation to the heat of the oven.
